UNITED STATES PATENT OFFICE

2,539,830

LIFT BAR MECHANISM FOR WINDOW BLINDS

Willis F. Hackedorn, Jr., Lakewood, Ohio, assignor to The Cordless Blind Company, Cleveland, Ohio, a corporation of Ohio

Application April 5, 1949, Serial No. 85,601

5 Claims. (Cl. 160—172)

1

This invention relates to Venetian or other types of window blinds of the type that are raised and lowered by manual manipulation of a bottom lift bar and more particularly to an automatic locking or braking mechanism for the lift bar.

My improved lift bar lock mechanism is adapted to be disposed internally of the lift bar and to operate in conjunction with the lift bar for permitting relatively free manual upward movement of the bar during raising of the blind while automatically preventing downward or lowering movement of the bar to hold same in any adjusted position. Accordingly, it is among the objects of my invention to provide a rugged, inexpensive and efficient lift bar locking mechanism that will automatically prevent downward movement of the lift bar except when manually released but will permit free upward movement thereof at all times.

Another object of my invention is to provide a compact self-locking and self-releasing lift bar lock mechanism which may be fabricated as a sub-assembly unit and conveniently assembled on the job when the blind is being installed.

These and other objects of my invention will appear from the following description of an embodiment thereof, reference being had to the accompanying drawings in which:

Figure 1 is an elevation of a Venetian blind assembly and a window frame, my improved lock or brake being incorporated in the lift bar;

Figure 2 is an enlarged fragmentary side elevation of a portion of the lift bar;

Figure 3 is an enlarged vertical cross-sectional view of the central portion of my lift bar, illustrating the brake or lock in locked position and taken substantially on the line 3—3 of Figure 4;

Figure 4 is a cross-sectional view taken substantially on line 4—4 of Figure 3;

Figure 5 is a detached perspective view of the lock unit guide piece;

Figure 6 is a perspective view of the central portion of the lift bar which houses my lock mechanism;

Figure 7 is a detached side elevation of the cam member;

Figure 8 is an end view of Figure 7 with the upper portion of the cam member shown in cross-section;

Figure 9 is a longitudinal cross-sectional view of the hub element;

Figure 10 is a sectional view of the hub element taken substantially on line 10—10 of Figure 9; and

Figure 11 is a detached side elevational view

of the lock release lever with a portion of the shank or hub thereof shown in cross-section.

Referring now to Figure 1, reference character 1 designates a window frame with which a Venetian blind 2 is associated. The Venetian blind 2 in which I have incorporated my present invention is of the so-called "cordless" type and includes a head box 3 mounted at the upper edge of the window frame 1. A suitable slat tilting and tape supporting means, not shown in detail, is housed in the head box 3 and the lower of the tapes are secured to the tubular lift bar 5 which will be more fully described later.

The tapes 4 support the slats 6 in the usual and well known manner and the tilt cords 7, which operate the tilt mechanism in the head box 3, provide the means for manually tilting the slats 6. Since the slat supporting tilting mechanism may be of any suitable type and as 20 it is not, per se, a part of the present invention, I have not described it in detail.

Side channel members 8 and 9 are secured to opposite sides of the window frame 1 and are adapted to receive the end portions 10 and 11 respectively of the lift bar 5 for guiding same during vertical movement. Portions of the guide tapes 12 and 13 are also disposed within the channel members 8 and 9 and may be of any suitable type such as fabric, flexible metal, etc. Tape 12 is supported at its upper end by a clip 14, see Figure 1, located near the upper end of channel 8, and extends downwardly within channel 8, passes through the tubular lift bar 5 from left to right and out of the right hand (Figure 1) end thereof, and finally is connected at its lower end to a clip 15 at the lower end of channel 9. In like manner guide tape 13 is connected to clip 16 located near the upper end of channel 9, passes downwardly within side channel member 9, enters the right end (Figure 1) of the lift bar 5, passes out of the left end thereof, and is anchored at its lower end to clip 17 at the bottom of the channel 8. The manner in which the guide tapes 12 and 13 operate in conjunction with the lift bar 5 will be explained more fully later.

The lift bar 5 comprises an assembly of identical end portions 10 and 11 which telescope into the opposite ends of a central body portion 19 as clearly shown in Figures 1 and 2. The central body portion 19 of the lift bar has fluted or ribbed side walls for providing greater rigidity and strength in the unit, see Figure 6, and the end portions 10 and 11 are secured in position by means of screws 20 and 21 which extend through

slot 22 in the bottom of the central body portion 19, see Figure 6, into threaded holes in end portions 10 and 11. These detachable end portions 10 and 11 permit the section 19 to be cut to the proper length to fit the window on which the blind is installed.

The end portions 10 and 11 of the lift bar 5 have pairs of guide rollers 23 and 24 and 23' and 24' respectively, which are rotatably supported at the outer ends of portions 10 and 11 and over which the guide tapes 12 and 13 pass as they enter and leave the lift bar 5. Guide rollers 23 and 24 are rotatably mounted on shafts 25 and 26, Figure 2, and rollers 23' and 24' are similarly mounted. The roller shafts are disposed to extend transversely of the end portions 10 and 11 and insure that minimum friction will be offered to the guide tapes 12 and 13 as bar 5 is raised or lowered. The end portions 10 and 11 are identical in all respects and may be interchanged and reversed end for end if desired.

The central body portion 19 of the lift bar 5 is adapted to receive a lock unit mechanism generally indicated at 28 in Figures 1 and 2, and shown on an enlarged scale in Figures 3 and 4. It is well to note at this point, that the guide tapes 12 and 13 must cross each other within the lift bar, as will be described in more detail later, and pass through the lock unit 28 in which they are acted upon by elements thereof in a manner to be described shortly. The central body portion 19 is provided with screw holes 29 and 30, see Figure 6, which are adapted to receive securing screws 31 and 32 for holding the lock unit 28 in position.

The lock unit 28 is a sub-assembly which is insertable as a unit in the hollow central body portion 19 of the lift bar 5. It includes a guide piece, generally indicated at 33, see Figure 5, by which the individual parts of the locking mechanism are supported and which has substantially parallel side walls 34 and 35, end walls 36 and 37, and a bottom wall or tape supporting plate 38. Side wall 35 has an aperture 39 located near its upper central portion and wall 34 has a similar but reduced aperture 40 located near its upper central portion and aligned with aperture 39. Each of the end walls 36 and 37 have inwardly struck guide tape tangs, 41 and 42 respectively, located near the bottom portion of each end wall. The tangs 41 and 42 extend substantially parallel to the tape supporting plate 38 and define therebetween openings 43 and 44 respectively, through which the guide tapes 12 and 13 pass when the lock unit mechanism 28 is assembled within the body portion 19 of the lift bar 5. The innermost end of each tang is bent upwardly as indicated at 45 and 46 respectively to provide smooth surfaces against which the tapes may rub and to eliminate the possibility of snagging of the top tape on the tang ends. End wall 36 is also provided with a transverse slot 47 and a vertically extending notch 48 located approximately at mid-height thereof for anchoring one end of spring 76 of the locking mechanism as will be explained later.

Disposed between the side walls 34 and 35 of the guide piece 33 is cam member 50 which is shown assembled in the lock unit 28 in Figure 3 and detached in Figures 7 and 8. The cam 50 has a solid bottom body portion 51 and a U-shaped upper portion 52. The U-shaped portion 52 is made up of two upwardly extending substantially parallel side walls 53 and 54 and top surface 55 of the bottom portion 51, see

Figure 8. Walls 53 and 54 are provided with aligned apertures 56 and 57, the axis of which constitutes the axis of rotation of the cam member 50. The apertures 56 and 57 are substantially circular with the exception of a flat portion designated 58, see Figure 7, which constitutes a keying means for non-rotatably mounting the cam member 50 on hub 63 as is described more fully below.

10 The bottom portion 51 of cam member 50 is provided with an irregularly curved cam surface 60 which is clearly shown in Figures 7 and 8. The profile configuration of surface 60 is such that the radial distance from the center of rotation progressively increases from substantially a minimum at a point 62 on the right side of the surface as viewed in Figure 7 to substantially a maximum at point 61 on the left side thereof.

20 Cam member 50 is supported within the side walls 34 and 35 of guide piece 33 by means of a hub 63, shown clearly in Figures 4, 9, and 10, which is rotatably supported at its ends in apertures 39 and 40 of the side walls 35 and 34, respectively, of the guide piece 33. The hub 63 has a reduced end 64 which fits into the hole 40 of the guide piece 33. The shoulder 64a abuts the inner face of wall 34 and prevents axial movement of the hub 63 to the left (Figure 4) when the parts are assembled. The hub also has a bearing portion 65, whose external surface is substantially cylindrical except for a flat portion 66, is rotatably supported in aperture 39 of guide member 33 and the flat portion 66 of the hub is oriented to engage the flat portions 58 and 59 of apertures 56 and 57 in cam member 50, so as to key the hub 63 and the cam member 50 together.

30 The external surface of bearing portion 65 of the hub 63 is also provided with an annular groove 67 for receiving spring clip 68 which serves to hold the hub in assembled position within the side walls 34 and 35 of the guide piece 33 (see Figures 3 and 4).

40 A tapered recess 69 in the bearing portion 65 of the hub 63 is adapted to receive the complementary tapered shank 70 of release lever 71 shown in Figure 11. The shank 70 has a central bore 72 through which a threaded securing screw 73 extends. When screw 73 is threaded into the threaded hole 74 in the reduced end 64 of the hub 63 the shank 70 will be drawn into tight non-rotatable engagement with the tapered surface of recess 69 of hub 63. The lever 71 is preferably counter bored at 75 (see Figure 4) in order to receive the head of the securing screw 73.

50 A looped wire spring 76 is disposed about the hub 63 and has two pressure arms 77 and 78 which engage the guide piece 33 and the cam member 50 respectively whereby to exert a constant pressure upon the latter tending to rotate it in tape locking or jamming direction (counterclockwise as seen in Figure 3). Spring arm 65 77 is adapted to fit into the notch 48 of recess 47 in the end wall 36 for easy assembly and arm 78 bears against bottom portion 55 of the cam member 50.

60 As heretofore mentioned, guide tapes 12 and 13 extend through the guide piece 33, entering and leaving the same through openings 43 and 44 at each end thereof. Since each guide tape extends from an upper corner of the window frame through the lift bar 5 to the lower corner 70 75 of the other side of the window frame, they nec-

essarily cross each other at some point within the lift bar 5. The cross over point is indicated at 79 in Figure 2 and is located to the left of the guide piece 33. Thus, as the tapes enter the left opening 43 in the guide piece they will be arranged in a superimposed vertically aligned relation, with tape 13 on top of tape 12. The superimposed relation between guide tapes 12 and 13 exists as long as the tapes are within the walls of the guide piece 33. A passage 80 is formed between the peripheral surface 60 of the cam member 50 and the tape supporting plate 38 of the guide piece through which guide tapes 12 and 13 extend. The peripheral surface 60 of cam member 50 is urged into engagement with the top tape 13 by the action of spring 76 (see Figure 3) and in this manner contact between the top tape 13 and the cam member 50 is normally maintained.

The automatic locking action of the cam member 50 on the tapes takes place as follows: As the lift bar is raised the guide tape 13 will have movement to the left (Figures 1, 2 and 3) relative to the bar 5. Movement of tape 13 in this direction will produce a tangential force on cam surface 60 due to the frictional engagement therebetween urging the cam member to rotate in clockwise or tape releasing direction against spring 76. Such clockwise movement of the cam member will tend to enlarge passage 80 because of the shape of the surface 60, and permit relatively free movement of the tapes 12 and 13 relative to each other and relative to the lift bar mechanism.

When upward movement of lift bar 5 is stopped and lifting force removed therefrom it tends to move downwardly under the influence of gravity. As soon as it starts down, however, the relative movement of the guide tapes 12 and 13 with respect to the guide piece 33 is reversed from that just described, that is, guide tape 13 will move toward the right, as viewed in Figures 1 and 3, and tape 12 will move to the left. The effect of such movement of the top tape 13 to the right when passing under and in contact with cam surface 60 is to rotate the cam member 50 in a counter-clockwise tape locking or jamming direction. This rotation of the cam member 50 diminishes the height of passage 80 through which the guide tapes pass and effects a wedging or jamming together of the guide tapes between cam surface 60 and bottom wall 38 of the guide piece. This wedging action is effective to lock the parts against further movement of the guide tapes relative to lift bar 5 and thus lowering movement of the lift bar and window blind is prevented.

Lowering of the lift bar 5 and blind assembly can be accomplished whenever desired by urging, as by thumb pressure of the operator, release lever 71 upwardly as viewed in Figure 2. Since the release lever is non-rotatably locked to the hub 63, which in turn is keyed to cam member 50, upward movement of the lever 71 from the position shown in Figure 2 causes a clockwise rotation of the cam member and, as explained above, will permit the guide tapes to move freely between cam surface 60 and the tape supporting plate 38 of the guide piece. As soon as lever 71 is released by the user, spring 76 will act against the cam member 50 to rotate the same into engagement with the top guide tape whereby to bring the automatic one way locking system described above into operation.

My improved lift bar lock mechanism contemplates a sub-assembly unit which is made up of

all the parts carried by guide member 33 except operating lever 71. During installation of a blind the tapes 12 and 13 are positioned in this sub-assembly as seen in Figure 3 and the sub-assembly is then located in the body portion 19 of bar 5, by sliding it in from one end, with hole 39 adjacent and aligned with hole 39' (see Figure 4). Next the shank 70 of lever 71 is passed through hole 39' into tapered bore 69 of hub 63, lever 71 set at the desired angular position, and then screw 73 inserted and tightened to lock the lever to the hub 63 so that it will operate cam 50. This arrangement greatly facilitates threading of the tapes through the lift bar control mechanism.

While I have described the illustrated embodiment of my invention with some degree of particularity, it will be understood that I do not wish to be limited to the particular mechanism herein shown and described and that various changes can be made to the illustrated form of my apparatus without departing from the spirit of my invention. For example, guide tapes 12 and 13, although illustrated herein as flat fabric tapes, could be made in the form of chains, flexible wire cables, or the like, and cam surface 60 could be suitably surfaced to properly engage same. I therefore claim as my invention all embodiments thereof coming within the scope of the appended claims.

I claim:

1. In a lift bar for a Venetian blind or the like comprising a tubular body member, a guide piece removably disposed within said tubular member and having side walls and a bottom wall, said side walls have aligned apertures near the top thereof, guide tapes extending through said guide piece in superimposed relation adjacent the bottom wall thereof and movable with respect thereto and to each other as said lift bar is raised and lowered, a hub element rotatably mounted in said apertures, means for retaining said hub element in said apertures, a cam member carried by said hub element for rotational movement therewith and having a cam surface disposed to engage one of said tapes, spring means for normally holding said cam surface in engagement with said one of said tapes, said one of said tapes being adapted to urge said cam member to rotate into jamming relation to said guide tapes as said lift bar is lowered while urging said cam member to rotate out of jamming relation to said tapes as said lift bar is raised, and manually operable means projecting from said tubular member for moving said cam member out of jamming relation to said tapes.

2. In a lift bar for Venetian blinds or the like, a tubular body member, a cam member rotatably supported within said body member, said cam member having a tape locking cam surface the radial dimension of which progressively increases from a minimum to a maximum, a tape supporting plate spaced from said cam surface, the axis of rotation of said cam member being substantially parallel to said supporting plate whereby rotation of said cam member will cause the space between said cam surface and said supporting plate to increase or diminish, means for directing a pair of guide tapes through the space between said cam surface and supporting plate in superimposed relation, spring means for urging said cam member to rotate in one direction to reduce said space between said cam surface and said supporting plate, and manually operable release means non-rotatably and removably connected with said cam member and projecting from said

tubular body member, said release means being adapted to move said cam member in a direction opposite said one direction to increase said space between said cam surface and said supporting plate.

3. In a lift bar for a Venetian blind or the like comprising a tubular body member, a guide piece removably disposed within said tubular member and having side walls and a bottom wall, a hub element rotatably supported by the side walls of said guide piece, a cam member carried by said hub element for rotational movement therewith, said cam member having a tape locking cam surface the radial dimension of which progressively increases from a minimum to a maximum, the axis of rotation of said cam member being substantially parallel to said bottom wall of the guide piece and said cam surface being spaced from said bottom wall whereby rotation of said cam member will cause the space between said cam surface and said bottom wall to increase or diminish, guide tapes extending and passing through the space between said cam surface and said guide piece bottom wall in superimposed relation, means for urging said cam member to rotate in one direction to reduce said space between said cam surface and said bottom wall, and a manually operable release lever projecting from said tubular body member and having a shank disposed in non-rotational engagement with said hub element whereby said lever is adapted to move said cam member in a direction opposite to said one direction to increase said space between said cam surface and said bottom wall.

4. In a lift bar for a Venetian blind or the like comprising a tubular body member, a guide piece removably disposed within said tubular member and having side walls and a bottom wall, a hub element rotatably supported by the side walls of said guide piece, said hub element having a recess therewithin, a cam member carried by said hub element for rotational movement therewith, said cam member having a tape locking cam surface the radial dimension of which progressively increases from a minimum to a maximum, the axis of rotation of said cam member being substan-

tially parallel to said bottom wall of the guide piece and said cam surface being spaced from said bottom wall whereby rotation of said cam member will cause the space between said cam surface and said bottom wall to increase or diminish,

5. In a lift bar for a Venetian blind or the like comprising a tubular body member, a guide piece removably disposed within said tubular member and having side walls and a bottom wall, a hub element rotatably supported by the side walls of said guide piece, a cam member carried by said hub element for rotational movement therewith, said cam member having a tape locking cam surface the radial dimension of which progressively increases from a minimum to a maximum, the axis of rotation of said cam member being substantially parallel to said bottom wall of the guide piece and said cam surface being spaced from said bottom wall whereby rotation of said cam member will cause the space between said cam surface and said bottom wall to increase or diminish, guide tapes disposed within said space in superimposed relation, means for urging said cam member to rotate in a direction to reduce said space between said cam surface and said bottom wall, and a manually operable release lever projecting from said tubular body member and having a shank, said shank being removably disposed within said hub recess in non-rotatable engagement with the hub element.
- 10 6. In a lift bar for a Venetian blind assembly having guide tapes for supporting said assembly, locking means disposed within said bar including a tape guide member having a bottom wall for guiding said tapes through said bar, a cam member carried by said guide member for limited rotation therein and having a tape locking peripheral cam surface in close proximity with said bottom wall, said tapes being disposed between and in contact one with said cam peripheral sur-
- 20 15 face and the other with said bottom wall of the guide member, spring means for urging said cam member into locking engagement with said one of said tapes, said cam member having an unlocked position near one limit of rotation thereof whereby to permit free upward movement of the lift bar and a locked position near the other limit of rotation thereof whereby to prevent downward movement of the lift bar, and manually operable means projecting from said bar and non-rotat-
- 25 20 ably connected with said cam member for moving same to said unlocked position.
